UNITED STATES PATENT OFFICE.

JAMES C. BAINE, OF MICHIGAN CITY, INDIANA, ASSIGNOR TO EXCELSIOR CYCLE COMPANY, OF MICHIGAN CITY, INDIANA, A CORPORATION OF ILLINOIS.

DESIGN FOR A BICYCLE FRAME.

Application filed December 6, 1920. Serial No. 428,820. Term of patent 14 years.

To all whom it may concern:

Be it known that I, JAMES C. BAINE, a citizen of the United States, residing in Michigan City, county of Laporte, and State of Indiana, have invented a new, original, and ornamental Design for Bicycle Frames, of which the following is a specification, reference being had to the accompanying drawing, forming part hereof.

The figure is a view in broken side elevation of a bicycle-frame, showing my new design.

I claim: The ornamental design for a bicycle-frame, as shown.

JAMES C. BAINE.
